FOLDABLE FLASH BULB UNIT FOR CAMERAS

Sidney Freed, Silver Spring, Md.

Application October 13, 1958, Serial No. 52,948

Term of patent 14 years

(Cl. D61—1)

FIG. 1.

FIG. 2.

FIG. 3.

FIG. 4.

FIG. 5.

FIG. 6.

Fig. 1 is a front elevational view of a folded foldable flash bulb unit for cameras showing my new design.

Fig. 2 is a rear elevational view thereof.

Fig. 3 is a right side elevational view thereof.

Fig. 4 is a left side elevational view thereof.

Fig. 5 is a top plan view thereof.

Fig. 6 is a bottom plan view thereof.

I claim:

The ornamental design for a foldable flash bulb unit for cameras, as shown.
